UNITED STATES PATENT OFFICE.

JOHN M. ADAMS, OF CHICAGO, ILLINOIS.

DESIGN FOR A HEAD OR FOOT FOR BEDSTEADS.

SPECIFICATION forming part of Design No. 29,639, dated November 8, 1898.

Application filed October 9, 1897. Serial No. 654,726. Term of patent 7 years.

To all whom it may concern:

Be it known that I, JOHN M. ADAMS, a citizen of the United States, and a resident of Chicago, in the county of Cook and State of Illinois, have invented and produced a new, useful, and original Design for the Head or Foot of a Bedstead, of which the following is a specification.

In the accompanying drawing the figure is a perspective view of the head or foot of a bedstead embodying my design, the essential features thereof being shown in full lines and ancillary features in dotted lines.

The head or foot of a bedstead embodying my design comprises posts or pillars A, an end rail A', and an open-work panel supported between the upper ends of the posts or pillars A, which in turn comprise transverse rods A² A³, which connect said posts A at or adjacent to their tops, and between these ends, respectively, upright rods A⁴, which connect said transverse rods A² A³ adjacent to their ends, and rods or elements A⁵ A⁶ A⁷, supported upon said transverse rods A² A³ and disposed so as to form a symmetrical ornamental design.

The essential feature of the head or foot of a bedstead of my design consists in the shape or configuration of the ornamental design formed by the elements A⁵ A⁶ A⁷, (shown in full lines in the drawing,) the element A⁵ forming the central portion thereof and the elements A⁶ A⁷ being in duplicate and being arranged or disposed correspondingly on opposite sides of said central element A⁵, so as to maintain the symmetry of the design.

The central element A⁵ of my design is a

bow or loop the sides of which meet at a point a, at which point they are attached to the rod A³, the curve of said bow or loop being reversed at a' and merging into substantially straight end portions a², which diverge from the point a at a slight angle.

The elements A⁶ diverge upwardly and outwardly from the common point a, between which point and points a³, at which they are attached to the transverse rod A², they form substantially ogee curves, being convex toward the bow or loop formed by the elements A⁵ at their lower ends and convex toward said bow or loop at their upper ends. The portions of said elements A⁶ beyond the points a³ form curves continuous with the upper concave portions of said elements and form therewith coils or helices. The elements A⁷ likewise diverge upwardly and outwardly from the common point a in upwardly-convex curves, terminating in coils or helices.

In general terms the ornamental design formed by the elements A⁵ A⁶ A⁷ may be described as a "fleur-de-lis" or "lily" design.

I claim—

The design for the head or foot of a bedstead, substantially as herein shown and described.

In testimony that I claim the foregoing as my invention I have hereunto set my hand, this 2d day of October, 1897, in the presence of two witnesses.

JOHN M. ADAMS.
